(57) **CLAIM**

The ornamental design for a cover for a battery case, as shown and described.

DESCRIPTION

FIG. 1 is an isometric view of a cover for a battery case showing our new design;

FIG. 2 is a front view of the cover for a battery case shown in FIG. 1;

FIG. 3 is a rear view of the cover for a battery case shown in FIG. 1;

FIG. 4 is a right side view of the cover for a battery case shown in FIG. 1;

FIG. 5 is a left side view of the cover for a battery case shown in FIG. 1;

FIG. 6 is a top view of the cover for a battery case shown in FIG. 1; and,

FIG. 7 is a bottom view of the cover for a battery case shown in FIG. 1.

The broken lines are shown for the purpose of illustrating portions of the article which form no part of the claimed design.
